REISSUED

ACCUMULATOR SHELL SEALING PLUG

Jean Mercier, New York, and Edward M. Greer,
West Hempstead, N. Y.; said Greer assignor to
Greer Hydraulics, Inc., Brooklyn, N. Y.

Application July 6, 1945, Serial No. 603,546

3 Claims. (CL. 138—30)

2

1
This invention relates to accumulators as used in the hydraulic system of airplanes but more particularly to the component parts of the accumulator and the manner of assembling those parts.

An accumulator is a fluid storage device that is connected to a hydraulic system, its principal function is to provide a surplus supply of the fluid in the system stored at a predetermined pressure so that any leakage in the system is automatically compensated for by the accumulator. The construction of an accumulator is usually a pressure vessel with a dividing yieldable wall, so that air pressure may be charged through a valve to the one side of the yieldable diaphragm and a fluid under pressure may be charged to the other side of the diaphragm. In another form of an accumulator a deformable bag or bladder is used instead of a diaphragm. The bag is affixed to one end of the shell by means of the small air valve stem. The opposite end of the shell is provided with an oil port. In this type of construction the deformable bag must be inserted through the larger opening of the oil port and the small air valve passed through a small perforation in the opposite end of the shell. It has been found advantageous to provide a rather large opening at the oil port end of the shell to facilitate the assembly of the bag in the accumulator. In providing a large opening there has arisen other difficulties namely the provision of a safe and tight plug. Safe in that it will not blow out under extreme pressures within the shell and tight so that it will not permit leakage of fluid. The usual manner of closing the oil port end of the accumulator is to provide a large neck end integral with the shell and internally threaded, into this opening a plug is threadably secured and this plug is provided with the correct size oil port. There are various disadvantages to this type of plug namely the threads may become worn or stripped and weaken the strength of such threads and when a maximum pressure is attained in the accumulator the plug may be blown out, another difficulty arises in disassembling, that is, the mechanic does not always relieve all the air pressure from the bag and consequently when the plug is partially released by the mechanic it suddenly blows out and may cause injury.

This invention has for an object the provision of an accumulator that is provided with a locking means for the sealing plug at the oil port end.

Another object of this invention is the pro-

vision of means to necessitate pushing the oil port plug inward against any resistance to its removal before the plug may be removed.

A still further object of this invention is to provide a quick and easily installed oil port plug that is safely secured to the shell of the accumulator.

Other objects may be apparent by reference to the accompanying drawings and detailed description in which,

Fig. 1 is a cross sectional view of the accumulator, and

Fig. 2 is a plan view of the locking ring.

In the embodiment of the invention illustrated in Fig. 1 there is a pressure resistant shell 10 with two opposed ports or mouths 11 and 12, the smaller port 11 is provided for a stem 13 of a standard pneumatic valve 15 and the larger port 12 is formed large enough to pass an accumulator bag 14 therethrough. The bag 14 is formed slightly pear shape or at least smaller than the internal periphery of the shell 10 and is provided with the standard pneumatic valves 15 moulded into the larger end portion of the bag. A circular strainer plug 16 is provided having its largest diameter "A" (indicated in dotted lines) slightly less than the diameter "B" (indicated in dotted lines) of the large port 12. The strainer plug 16 is formed with a large perforated head portion 17 and an extended neck portion 18 that is somewhat smaller in diameter to allow a seal 20 to be interposed between the neck portion 18 of the plug 16 and the shoulder of the port 12. The neck portion 18 is internally threaded to permit an oil port plug 21 to be threadably secured, this plug 21 having the port 22 for securing the fluid line thereto. The neck 18 of plug 16 is also externally threaded so that an external nut 23 may be secured thereto. The portion of plug 16 where the neck 18 and the head 17 meet forms a circular shoulder portion 24. A locking ring 25 illustrated in Fig. 2 is provided and is formed with an inside diameter equal to the external diameter of the extended neck portion 18 of the plug 16 of Fig. 1. The ring 25 is also formed with a slight curvature 26 on its upper face as indicated in Fig. 1 so that it fits into the shoulder 24 of the plug 16. The outside diameter of the ring 25 is greater than the diameter "B" of the port 12. The ring 25 is cut through one portion of its circumference as at 27 to permit the installation of this ring through the port 12 which is of smaller diameter. This is done by springing the ring or compressing it, then after it is within the shell it may be expanded.

In assembling the accumulator the shell 10 is empty and a bag 14 may be passed through the opening 12. The valve stem 13 is pushed up through the opening 11 and a washer and nut are secured to the outside stem and threaded down to clamp the stem in the position indicated in Fig. 1. The plug 16 is then passed through the port 12 and the ring 25 is next compressed and passed through port 12, the ring 25 is then expanded and passed over the neck portion 18 of the plug 16. The plug 16 is then brought down to the position indicated in Fig. 1. The seal 20 is next pressed into the opening 12 around the neck portion 18 of the plug 16. The nut 23 is next threaded on to the external threads of the neck 18 and drawn up tightly to hold the whole assembly 16 in a rigid, tightly sealed relationship. The accumulator is then ready to have the fluid port plug 21 secured thereto and the port 22 connected to a fluid system. The bag 14 is inflated with a prescribed pressure before the accumulator is put into operation.

In disassembling this accumulator, it is absolutely necessary to release all air pressure from the bag 14, as in removing the plug 16 it is necessary to push it inward so that the ring 26 may be slipped from the neck 18 and compressed to remove it through opening 12. The plug 16 may then be removed. It is apparent that a mechanic cannot remove the plug 16 with air pressure remaining in the bag 14, therefore there is no danger of injury from the plug being blown out during disassembly.

Although a preferred form has been shown it is understood that a mechanic working within the scope of which is claimed, may make changes without departing from the spirit of this invention.

What is claimed is:

1. In an accumulator comprising a shell having two ports, a deformable partition secured

5 within said shell separating said two ports from each other, a strainer plug placed inside the larger of said ports, a split spring locking ring of greater diameter than said largest port placed inside said port, means to secure said strainer plug and locking ring in juxtaposition with the said shell at the periphery of the large port.

2. In an accumulator comprising a shell having two ports, a deformable partition secured within said shell separating said two ports, a strainer plug placed inside one of said ports, a split spring locking ring of greater diameter than said port into which said strainer plug is placed, means to seal said strainer plug and locking ring in juxtaposition with the said shell at the periphery of the one port.

3. An accumulator according to claim 2 having means to release the air pressure from said air portion to release the force of said deformable partition on said strainer plug, and means to manually remove said split spring locking ring by pushing it inward toward said deformable partition so that said split spring may be compressed and removed through said mounting port to permit removal of said strainer plug.

JEAN MERCIER.

EDWARD M. GREER.
